ROLLER

Emmett A. Henley, Bakersfield, Calif.

Application January 18, 1944, Serial No. 518,729

7 Claims. (Cl. 16—99)

This invention relates to a caster type roller construction that may be utilized to movably support articles of furniture or other heavy articles.

A primary object of the invention is to provide a disappearing roller which, when the article of furniture on which the device is mounted, is stationarily positioned disappears within the body of the construction allowing the article to rest solidly on the floor or other supporting surface, but which when the article is moved becomes effective to elevate the article from the supporting surface and rollably support the same to facilitate its movement from one location to another.

More specifically an object of the construction is to provide a caster type roller consisting of a roller having trunnions with inclined surfaces engageable with the periphery of the roller to facilitate elevation of the article of furniture, and which has rail portions adjacent the lower ends of the inclined surfaces adapted to supportingly engage the trunnions whereby the weight of the article is transferred from the periphery of the roller to the trunnions when the article of furniture has been elevated into its movable position.

With the foregoing and other objects in view, which will be made manifest in the following detailed description and specifically pointed out in the appended claims, reference is had to the accompanying drawing for an illustrative embodiment of the invention, wherein:

Figure 1 is a sectional view of the device embodying the present invention illustrating the article of furniture on which the device may be mounted with the article of furniture in its stationary position wherein it is resting solidly on the floor or other supporting surface;

Fig. 2 is a view similar to Fig. 1, but illustrating the parts in that position wherein the article of furniture has been elevated and is in a position to be rolled;

Fig. 3 is a vertical section taken substantially upon the line 3—3 upon Fig. 2, in the direction indicated; and

Fig. 4 is a partial view similar to Fig. 2, illustrating a slightly modified form of construction.

Referring to the accompanying drawing wherein similar reference characters designate similar parts throughout, A indicates any article of furniture or other heavy object that it is desired to occasionally move from place to place.

The caster or roller construction embodying the present invention is preferably formed of three body parts, the center body part being in-

dicated at 10 and the side body parts indicated at 11 and 12. These body parts may be secured together such as by bolts, rivets, or the equivalent indicated at 13. On the underside of the central body part 10 there are formed two downwardly inclined surfaces indicated at 14 and 15, these being oppositely inclined from adjacent the center of the body part and extending downwardly toward its ends. A roller 16 is provided, the diameter of which is approximately equal to the distance between the apex 17 and the bottom surfaces 18 at the ends of the side body parts 11 and 12 so that this roller may occupy a position wholly within the body as illustrated in dotted lines on Fig. 2. Preferably the roller carries a thin rubber tire 19 although, if desired, the body of the roller may be completely formed of rubber. On the sides of the roller there are trunnions 20 preferably equipped with bushings 21.

The side body parts 11 and 12 present on their under surfaces bottom inclined surfaces 22 which extend downwardly and outwardly from an apex 23. These inclined surfaces are substantially parallel to the inclined surfaces 14 and 15. However, adjacent their ends they meet or merge with rail portions 24 which may be either horizontal or substantially so. If they are given a slight inclination as shown on Fig. 2, they are but slightly inclined inwardly toward the apex 23. The ends of the inclined surfaces 14 and 15 meet or merge with horizontal surfaces 25 at the ends of the central body part 10.

The construction is such that the vertical distance between surfaces 14 and 15 and their parallel surfaces 22 is slightly less than the vertical distance between surfaces 25 and the rail portions 24. Side plates 26 are provided having flanges 27 that may extend inwardly beneath the side body parts 11 and 12. These side plates may be fastened as by screws 28 to the sides of the side body parts and serve to maintain or confine the trunnions and the bushings thereon in the space beneath the inclined surfaces 22, the rail portions 24, and the flanges 27.

The operation and advantages of the construction above described are as follows: In the position shown in Fig. 1, the roller has completely disappeared within the body so that the article A may rest solidly on the floor or other supporting surface. If the body is moved from right to left the roller tends to wedge between the floor and the inclined surface 15. The weight of the article A is thus transmitted from the central body part 10 directly to the periphery of the

roller. Continued movement of the article A from right to left causes the inclined surface 15 to roll up on the roller thus elevating the article above the floor, as shown in Fig. 2. The rubber tire is advantageously employed in that it tends to promote such wedging action between the inclined surface 15 and the floor rather than merely have the roller skid or slide across the floor when pushed by the inclined surface 15. During the time that the inclined surface 15 is rolling up the roller the bushings on the trunnions do not engage the surfaces 22 so that there is no weight carried by the trunnions during this period of operation. When the inclined surface 15 has completely rolled up the roller the trunnions carry their bushings beneath the rail portions 24 on the side body members 11 and 12, thus effecting a transfer of the weight of article A from the periphery of the roller to the trunnions through the medium of the rails 24. In this position the article A may be pushed across the floor quite readily with the trunnions on the roller merely rotating or turning in their respective bushings. When the article has reached the desired location it may be pushed slightly from left to right causing the bushings to rotate with their trunnions and thus roll off of the rails 24 and the roller returns to its fully concealed position wherein the article is again resting solidly on the floor as shown in Fig. 1. Obviously, if the article is thereafter pushed from left to right inclined surface 14 will roll up on the roller in a reverse direction and at the lower end of the inclined surface 14 there will be a transfer of weight from the periphery of the roller to the trunnions.

By means of this construction the caster or roller is at all times concealed when the article A is in a stationary position. When it is desired to move the article this can be easily accomplished by merely pushing on the article and this results in elevating the article the required distance with great mechanical advantage. When the article is fully elevated and is supported by the trunnions it will be noted that the continued rotation of the roller occasioned by the continued movement of the article does not wear a notch or recess in the under surface of the rail portions 24. Such a notch or recess if worn would hinder return of the roller from the full line position shown in Fig. 2, to the dotted line position shown therein. When it is desired to cause the roller to return from the full line position shown in Fig. 2, to the dotted line position shown therein, reverse rotation of the roller occasioned by reversely moving the article only a short distance will cause the bushings to rotate frictionally with the trunnions off of the rail portions 24 so as to enable the inclined surface 14 or 15, as the case may be, to roll down the periphery of the roller.

In Fig. 4, there is shown a slight modification wherein the rail portions 24a may be, if desired, truly horizontal and the portions 25a may be outwardly and upwardly inclined instead of horizontal as shown in Fig. 2, providing the necessary clearance between the ends of the body section 10 and the periphery of the roller when the weight of the article is supported by the trunnions engaging the rail portions 24a.

From the above-described construction it will be appreciated that the improved roller or caster is a very simple and durable design, that its parts can be economically manufactured, and when used, it will serve to efficiently lift and transport an article on which it may be mounted.

It will of course be appreciated that there may be a wide variety of installations of the structure embodying the invention. In some installations the structure may be recessed in the article 5 A as shown and in others the construction may be merely attached to the article, such as an article of furniture and be merely secured in a largely concealed position to the framework of the article. Under such circumstances where the construction of the article is such as to effectively conceal the roller construction it is not necessary that it be recessed in the framework of the furniture.

Various changes may be made in the details 15 of construction without departing from the spirit and scope of the invention as defined by the appended claims.

I claim:

1. A device of the class described comprising 20 a roller adapted to roll on a supporting surface, means providing a downwardly inclined surface on an article adapted to be supported by the roller engageable with the periphery of the roller whereby, on moving the article relatively to the 25 supporting surface, said inclined surface will roll upwardly on the roller to elevate the article, trunnions on the roller, and means on the article adapted to be supportingly engaged by the trunnions when said inclined surface has rolled upwardly on the roller to have the weight of the 30 article transferred thereto.

2. A device of the class described comprising a 35 roller adapted to roll on a supporting surface, means providing a downwardly inclined surface on an article adapted to be supported by the roller engageable with the periphery of the roller whereby, on moving the article relatively to the supporting surface, said inclined surface will roll upwardly on the roller to elevate the article, trunnions 40 on the roller, and means on the article adapted to be supportingly engaged by the trunnions when said inclined surface has rolled upwardly on the roller to have the weight of the article transferred thereto, said trunnions having bushings thereon.

3. A device of the class described comprising a 45 roller having trunnions, means providing oppositely extending inclined surfaces engageable with the periphery of the roller, and means for effecting a transfer of the weight of the article supported by the roller to the trunnions at the ends of the downwardly inclined surfaces.

4. A device of the class described comprising a 50 roller having trunnions, means providing oppositely extending inclined surfaces engageable with the periphery of the roller, and means for effecting a transfer of the weight of the article supported by the roller to the trunnions at the ends of the downwardly inclined surfaces, said trunnions having bushings thereon.

5. A device of the class described comprising a 55 roller having trunnions equipped with bushings, means providing an inclined surface adapted to supportingly engage the periphery of the roller, and means adapted to supportingly engage the bushings on the trunnions at the lower end of the inclined surface so as to effect a transfer of weight from the periphery of the roller to the trunnions.

6. A device of the class described comprising a 60 roller having trunnions equipped with bushings, means providing opposed downwardly and outwardly inclined surfaces either of which is adapted to supportingly engage the periphery of the roller, and means providing rail portions adapted 65 70 75

to supportingly engage the bushings on the trunnions at the lower ends of either of the inclined surfaces so as to effect a transfer of weight from the periphery of the roller to the trunnions.

7. A device of the class described comprising a body presenting adjacent its center oppositely extending downwardly inclined surfaces, a roller adapted to have its periphery supportingly en-

gage either of said inclined surfaces, said roller having trunnions equipped with bushings, said body presenting rail portions at the sides of said inclined surfaces beneath the lower ends thereof adapted to supportingly engage the bushings on the trunnions when an inclined surface has rolled up on the roller.

EMMETT A. HENLEY.
